D20468

UNITED STATES PATENT OFFICE.

GEORGE HENRY PHILLIPS, OF GENEVA, NEW YORK.

DESIGN FOR A COOKING-STOVE.

SPECIFICATION forming part of Design No. 20,468, dated January 6, 1891.

Application filed December 13, 1890. Serial No. 374,630. Term of patent 7 years.

To all whom it may concern:

Be it known that I, GEORGE HENRY PHILLIPS, a citizen of the United States, residing at Geneva, in the county of Ontario and State of New York, have invented and produced a new and original Design for Stoves, of which the following is a specification, reference being had to the accompanying photograph, forming a part thereof.

10 The photograph is an isometric perspective of my invention and is deemed adequate to fully illustrate my design.

The leading feature of the design consists in a base having at its outer edge a series of 15 beads, projecting legs beneath the beads, scroll-work above the lower edge, and a ribbed or fluted top molding above the scroll-work, a body portion within the plane of the base having ribbed or fluted vertical bars, raised 20 panels on the body formed with rounding, fluted, or ribbed edges, a raised ornamental surface on one of the panels, and scroll-work at the edge of said raised surface, a shelf having a flaring base and top, a contracted central portion, beaded or ribbed sides and top edges, scroll-work adjacent to the beads, and a rounding central panel having raised scroll-work.

The base A is essentially rectangular in 30 form, having downwardly-extending legs A', formed with a rounding ornamented outer face. Beads or bars B extend lengthwise at the lower edge of the base, and just above the lengthwise beads are sections of scroll-work 35 C, which are separated by a series of shorter beads B'.

D represents the ribbed or fluted top bar of the base, which is of rounding cross-section. The appearance produced by this peculiar arrangement of beads, scroll-work, and ribbed 40 bar is very pleasing and adds a desirable finish to the base of the stove.

The body portion E of the stove is within the plane of the base, and formed thereon are vertical ribbed or fluted bars F.

G, G', and G² are raised panels on the body portion E, formed with one or more rounding corrugated edges g, the end panels G and G² having thereon ornamental scroll-work and the central one a raised surface H of an irregular outline and a configured outer face. At the edge of the surface H is a scroll-work I. At the top and bottom of the body E, at its side and front, are raised bars E', and between the said bars on the front of the stove 55 are panels E², having a configured outer surface formed of plane and curving surfaces and curved and straight lines.

J represents the shelf at the upper part of the stove, having a flaring top and base and a contracted center; j, the beaded sides and top edge of the shelf, and j' the scroll-work adjacent to the beads. At the top of the shelf J is a bar J', and beneath this bar is the raised panel K, having the raised scroll-work 60 L, consisting of a vertical central bar and compoundly-curved bars by intersecting the central bar.

The herein-described design is very pleasing in appearance, causes the stove to present 70 both a simple, neat, and ornamental appearance, and greatly adds to its salability.

What I claim is—

The design for stoves, substantially as herein set forth.

In testimony whereof I have hereunto signed my name, in the presence of two attesting witnesses, at Geneva, in the county of Ontario, in the State of New York, this 6th day of December, 1890.

GEORGE HENRY PHILLIPS.

Witnesses:

WALTER A. CLARK,
EDGAR PARKER.
